[57] CLAIM

The ornamental design for a battery charger pocket, as shown and described.

DESCRIPTION

FIG. 1 is a top front isometric view of a battery charger pocket showing my new design;

FIG. 2 is a top rear isometric view thereof;

FIG. 3 is a top plan view thereof;

FIG. 4 is a bottom plan view thereof;

FIG. 5 is a front elevational cross-sectional view taken along the lines 5—5 of FIG. 3;

FIG. 6 is a side elevational cross-sectional view taken along the lines 6—6 of FIG. 3;

FIG. 7 is a front elevational view, the rear elevational view being a mirror image thereof;

FIG. 8 is a left side elevational view, the right side elevational view being a mirror image thereof;

FIG. 9 is a side elevational cross-sectional view taken along the lines 9—9 of FIG. 7;

FIG. 10 is a side elevational cross-sectional view taken along the lines 10—10 of FIG. 7;

FIG. 11 is a front isometric view of a battery charger pocket showing my new design mounted in a panel;

FIG. 12 is a rear isometric view thereof; and,

FIG. 13 is a top plan view thereof.

The broken line showing of the panel in FIGS. 11, 12 and 13 is included for the purpose of illustrating environmental structure only and forms no part of the claimed design.
